UNITED STATES PATENT OFFICE

113,006

DESIGN FOR A COMBINED PLATFORM SCALE AND VENDING DEVICE

Claude R. Kirk, River Forest, Ill.

Application November 18, 1938, Serial No. 81,200

Term of patent 7 years

To all whom it may concern:

Be it known that I, Claude R. Kirk, a citizen of the United States and a resident of River Forest, in the county of Cook and State of Illinois, have invented a new, original, and ornamental Design for a Combined Platform Scale and Vending Device, of which the following is a specification, reference being had to the accompanying drawing, forming a part thereof, and in which:

The single figure is a perspective view of a combined platform scale and vending device showing my new design, the printed matter being merely illustrative.

I claim:

The ornamental design for a combined platform scale and vending device, as shown and described.

CLAUDE R. KIRK.
